HOLDER FOR LIPSTICK CONTAINERS

David S. Wyse, % Projects Unlimited, Inc., P.O. Box
1426, Northridge Station, Dayton, Ohio 45414

Filed Apr. 16, 1971, Ser. No. 134,927

Term of patent 14 years

Int. Cl. D3—99

U.S. Cl. D86—10

FIG-1

FIG-5

FIG. 1 is a perspective view of a holder, for lipstick containers showing my new design;

FIG. 2 is an opposite end elevational view thereof;

FIG. 3 is a top view thereof;

FIG. 4 is a rear view thereof; and

FIG. 5 is a bottom view thereof.

I claim:

The ornamental design for a holder for lipstick containers, substantially as shown.
